UNITED STATES PATENT OFFICE.

FREDERICK C. BAKER, OF PORTLAND, OREGON.

DESIGN FOR A LIGHTING-FIXTURE.

50,865.

Specification for Design.

Patented June 5, 1917.

Application filed April 30, 1917. Serial No. 165,625. Term of patent 7 years.

To all whom it may concern:

Be it known that I, FREDERICK C. BAKER, a citizen of the United States, residing at Portland, in the county of Washington and State of Oregon, have invented a new, original, and ornamental Design for a Lighting-Fixture, of which the following is a specification, reference being had to the accompanying drawings, forming part thereof.

The figure is a perspective view of a lighting fixture, showing my new design.

I claim:

The ornamental design for a lighting fixture, as shown.

FREDERICK C. BAKER.
